US0D1093581S

(12) **United States Design Patent** (10) **Patent No.:** **US D1,093,581 S**
(45) **Date of Patent:** **** Sep. 16, 2025**

(54) **FIRE PIT**

(71) Applicant: **Dick's Sporting Goods, Inc.**,
Coraopolis, PA (US)

(72) Inventors: **Casper A. Crouse**, Coraopolis, PA
(US); **Jenny Feng**, Coraopolis, PA
(US); **Craig F. Hofmann**, Pittsburgh,
PA (US)

(73) Assignee: **Dick's Sporting Goods, Inc.**,
Coraopolis, PA (US)

(**) Term: **15 Years**

(21) Appl. No.: **29/892,931**

(22) Filed: **May 23, 2023**

(51) LOC (15) Cl. **23-01**

(52) U.S. Cl.

USPC **D23/335**

(57) **CLAIM**

The ornamental design for a fire pit as shown and described.

DESCRIPTION

FIG. 1 is a perspective view of the claimed design;
FIG. 2 is a front view of the claimed design shown in FIG.
1;
FIG. 3 is a rear view of the claimed design shown in FIG.
1;
FIG. 4 is a side view of the claimed design shown in FIG.
1;
FIG. 5 is another side view of the claimed design shown in
FIG. 1;
FIG. 6 is a top view of the claimed design shown in FIG. 1;
and,
FIG. 7 is a bottom view of the claimed design shown in FIG.
1.

The evenly spaced broken lines shown in the drawings are
included for the purpose of illustrating portions of the fire pit
that form no part of the claimed design. The dot-dash-dot
lines shown in the drawings represent the boundary of the
claimed design.

1 Claim, 7 Drawing Sheets
